UNITED STATES PATENT OFFICE.

WILLIAM T. MURPHY, OF NEW YORK, N. Y.

DESIGN FOR A VASE.

SPECIFICATION forming part of Design No. 12,906, dated April 25, 1882.

Application filed March 10, 1882. Term of patent 7 years.

To all whom it may concern:

Be it known that I, WILLIAM T. MURPHY, a citizen of the United States, residing at the city, county, and State of New York, have invented and produced a new and original Design for Vases, of which the following is a specification, reference being had to the accompanying drawings, forming part thereof.

Figure 1 is a side view of a vase illustrating my design, and Fig. 2 is a horizontal section on the line 2 2 in Fig. 1.

The body of the vase is elliptical as viewed in side elevation, and the elliptical faces A are recessed, as shown in Fig. 2, leaving raised margins a a. The narrower edges or sides B of the vase are slightly convex, and upon them are formed a series of rounded projections, b b, which increase somewhat in size from the bottom toward the top. C is the foot or base of the vase, which is circular in plan and joined to the body by a neck-mold, c, and D is the mouth of the vase, which is also circular in

plan and joined to the body of the vase by a concave contracted neck, d.

Having thus described my design for a vase, I claim—

1. The design for a vase herein shown and described, the same consisting of the body of elliptical shape, provided with recessed elliptical faces A, and with a base or foot, C, and mouth D.

2. The design for a vase herein shown and described, the same consisting of an elliptical body provided with the recessed elliptical faces A, and its edges provided with the series of rounded projections b b, the foot C, and the mouth D.

In witness whereof I have hereunto signed my name in the presence of two subscribing witnesses.

WM. T. MURPHY.
